ABSTRACT OF THE DISCLOSURE

A mixing-dosing-distributing device for abrasive stuffs suspended in water comprising a vertical disc partially submerged in the suspension and rotating so that the abrasive stuff is transported by the disc to a height above the suspension where a spatula is provided to scrape the abrasive stuff off the disc and direct it to a distribution zone.

This invention concerns; a mixer-dosimeter-dispenser for abrasives and like, specially for lapping machines and like.

It is well known that in machines using abrasive materials mixed with liquids, there is the absolute need of ensuring that said abrasive be dispensed in a continuous and constant way, with a maximum of reliability as well as under the provision of a wide quantitative control.

On the contrary the situation is that mixers-dosimeters now in use do not include any system suitable for obtaining the typical guarantees for constance and continuity now referred to.

In some of the more known types the substance being in suspension into the liquid is made to pass through regulatable slits, but in a short time the passage is obstructed owing to bunching of said substance, with ensuing difficulties concerning the evenness of operation for the machine to be fed. Said difficulties, i.e. unevenness and discontinuity of feed, are particularly objectionable for lapping machines.

It is the main object of this invention to obviate the above referred to difficulty, through the adoption of a mixer-dosimeter-dispenser of abrasives mixed with liquids, for lapping machines and like, which may ensure the evenness and precise dosage of the abrasive material, the whole through simple and economical ways, which may also be easily controlled in operation.

These and other objects are obtained through the mixer-dosimeter-dispenser devised according to this invention, belonging to the type including a tank for receiving the abrasive in a liquid medium, and a stirrer, for instance of the paddle type, which is characterized in that it includes a dipping element, for instance a rotatable disc, set along a vertical plane, which emerges topwise from the surface of the liquid-abrasive mixture, at least one scraping spatule, suitable to be brought into contact with the upper portion of said disc, and one or more canals which gather the material being scraped upon the dipping element (disc) of the spatule and apportion the same to the machine in operation, such as a lapper or like.

Another feature of this invention lies in the special embodiment for the motion's transmission: one motor sets in rotations the paddle stirrer, or other, suitable device, providing a horizontal motion, and the extension topwise of the shaft of said stirrer transmits on its turn, by friction, the motion to the vertical carrier-disc. It may also happen that disc be driving and the central stirrer's shaft be driven.

It must be also added that spatule, or spatules, may be

2

oriented, so as to obtain, through their different contact position upon the dipping element, for instance a rotating disc, the control of quantity of abrasive to be distributed to the machine.

5 The invention shall now be better described with reference to an embodiment, being given only as a qualitative and not limitative example, and as shown in the enclosed drawing, in which:

FIG. 1 shows schematically, in a vertical section, the dosimeter-dispenser devised according to this invention; and

FIG. 2 shows schematically as well the dosimeter-dispenser as seen from its top.

With reference to the enclosed drawing, with 1 is shown the tank containing the abrasive substance, in suspension into the liquid 2, and with 3 the paddle stirrer or any other suitable system, which rotates horizontally slightly above the bottom 1a of tank 1. A vertical shaft 4, which passes through the bottom 1a and carries at its 20 end a pulley 5 which receives the motion from an engine (not shown) through a belt 6. Shaft 4 extends topwise within the tank 1 and is fixed to a drum 7 which has, at a given height, an annular enlargement 7a. The stirrer 3 is driven by the drum 7.

25 According to the invention there is provided within the tank 1, a disc 8, vertically placed and being idle, with its hub 8a around pivot pin 9 (FIG. 2), which is made fast to a side part of tank 1. Disc 8 has its fore surface (shown in FIG. 1) in contact with annular enlargement 30 7a, so that, when stirrer 3 is in motion, for instance as shown with arrow f₁ (FIG. 2), also drum 7 and enlargement 7a rotate along the arrow f₂ (FIG. 1), and therefore, by friction disc 8 may rotate along arrow f₃ (FIG. 1). As this disc 8 emerges for a good part from the surface 2a of the liquid containing the abrasive, in its rotation it will carry upwise a film of the said liquid, and therefore a certain amount, being constant and even, of abrasive.

35 Adjacent the upper part of disc 8 there is provided at 40 least one spatule 10, which scrapes the carried mixture and makes it fall upon a gathering rod 11 of circular section, so as to offer to the emery a circular surface which may not form deposits. From this rod 11 abrasive passes into a small canal 12, upon the middle plane of which 45 there is placed a second collecting rod 13, which dispenses it dropwise to the operating machine (not shown in the drawing).

According to this invention, the disposition and/or the 50 position of spatule 10 with reference to disc 8, may be varied, so as to occupy upon the same respectively a circular crown of different width, or to be at a different distance from the center of the disc itself. In this way one may change in a very simple way the quantity of abrasive being dispensed by the dosimeter.

55 This may be obtained by operating upon the support 14 of said spatule, which is rockingly adjustable in the said ways, upon a pivot 15, for instance through a knob 16, that turns a worm and worm gear.

Another possibility of regulation for the dosing of 60 abrasive is to be obtained through the variation of the rotation speed of disc 8. To this end one may provide a kinematic coupling through a pair of gears (not shown), between the driving shaft 4 and the drum 7, in order to obtain a different speed of the drum, and therefore of the disc 8, being the same the rotation speed of stirrer 3.

65 Although only one embodiment has been described for the invention, devised according to these concepts, it is clear that in practice many more may be suggested, always based upon the main concepts now referred to, which define the invention, without leaving the law-full protection of the invention itself.

What I claim is:

1. A mixer-dosimeter-dispenser for abrasives in a liquid medium, said dispenser comprising:
  - (A) A tank containing the abrasive in the liquid medium,
  - (B) A paddle stirrer in said tank,
  - (C) A disc,
  - (D) Means supporting said disc in said tank for rotation of a vertical flat face thereof about a horizontal axis, said supporting means being disposed so that the lower portion of said flat face is disposed beneath the surface of said liquid abrasive and the upper portion of said flat face is disposed above said surface,
  - (E) Means to continuously rotate said disc about said axis so that the upper portion of the flat face progressively moves into and under the surface of said liquid abrasive mixture and the lower portion of the flat face progressively emerges from the surface of said liquid abrasive mixture carrying liquid-abrasive mixture thereon,
  - (F) A spatula,
  - (G) Means to hold said spatula in bearing engagement with a part of the upper portion of said flat face so as to scrape continuously liquid-abrasive mixture therefrom,
  - (H) Means for distributing liquid-abrasive mixture to a utilization mechanism, and,
  - (I) Means for collecting liquid-abrasive material scraped from the flat face by the spatula and transferring the same to the distributing means.
2. A mixer-dosimeter-dispenser as set forth in claim 1 wherein:
  - (A) The paddle stirrer is adjacent the bottom of the tank and turns about a vertical axis,
  - (B) A vertical rotating shaft drives the stirrer and extends into the tank alongside said flat face of the disc, the longitudinal axis of said shaft intersecting the horizontal axis of rotation of said disc,

- (C) The continuous rotating means for the disc constitutes a drum turned by said shaft and an annular enlargement on said drum in frictional engagement with the flat face of the disc, and,
- (D) A horizontal pivot pin is carried by the tank and on which the disc rotatably idles, said pin constituting the disc supporting means.
3. A mixer-dosimeter-dispenser as set forth in claim 2, wherein the drum is mounted on and turns with said shaft.
4. A mixer-dosimeter-dispenser as set forth in claim 1, wherein means is included to vary the position of the spatula bearing on the flat face of the disc so as to vary the quantity of abrasive-liquid material being collected and supplied.
5. A mixer-dosimeter-dispenser as set forth in claim 1, wherein the spatula holding means includes means to selectively vary the position of the spatula about a horizontal axis perpendicular to the flat face of the disc so as to vary the quantity of abrasive-liquid material being collected and supplied.
6. A mixer-dosimeter-dispenser as set forth in claim 1, wherein the collecting means is an inclined circular rod having an upper portion arranged to receive abrasive-liquid mixture falling from the spatula and thereby provide a circular convex surface on which the abrasive will not form deposits.
